Term of patent 14 years

(Cl. D58—26)

Fig. 1.

Fig. 2.

Fig. 3.

Fig. 4.

FIGURE 1 is a side elevational view of a holder for cleansing liquid container and applicator or the like, showing our new design;

FIGURE 2 is a top plan view thereof;

FIGURE 3 is an end elevational view thereof; and

FIGURE 4 is a side elevational view thereof.

The dominant features of our design reside in the opening provided in the container holder wall, said opening having the configuration shown, and the narrow horizontal bridge being in a common plane with the top edges of the container holder and of the handle.

We claim:

The ornamental design for a holder for cleansing liquid container and applicator or the like, as shown and described.
